POWER-OPERATED HEDGE SHEAR

Arthur N. Emmons and John P. Bruck, Nedrow,
N. Y., assignors to Porter-Cable Machine Com-
pany, Syracuse, N. Y., a corporation of New
York

Application January 27, 1951, Serial No. 14,001

Term of patent 14 years

(Cl. D40—1)

To all whom it may concern:

Be it known that we, Arthur N. Emmons and John P. Bruck, citizens of the United States, residing at Nedrow, State of New York, have invented a new, original, and ornamental Design for a Power Operated Hedge Shear, of which the following is a specification, reference being had to the accompanying drawing, forming part hereof.

Figure 1 is a top plan view of a power operated hedge shear embodying our new design.

Figure 2 is an end elevational view looking upwardly in Figure 1.

Figure 3 is a rear elevational view looking downwardly in Figure 1.

Figure 4 is a side elevational view looking to the left, Figure 1.

Figure 5 is a side elevational view looking to the right, Figure 1.

We claim:

The ornamental design for a power operated hedge shear, as shown.

ARTHUR N. EMMONS.
JOHN P. BRUCK.
